UNITED STATES PATENT OFFICE.

ARTHUR R. SODERQUIST, OF IDAHO FALLS, IDAHO.

LOCK CLOSURE FOR ICE BAGS.

Application filed February 17, 1927. Serial No. 169,019.

This invention relates to ice-bags and more particularly to the closures therefor.

The invention has for one of its objects to prevent a patient from gaining access to and consuming the ice and water of an ice-bag during the absence of the nurse or other attendant, and to attain this end comprehends the provision of a novel and simple closure which cannot be removed except by a key in the possession of the nurse or attendant.

With the foregoing and other objects in view, the invention consists of the construction, combination and arrangement of parts hereinafter fully described and claimed, and illustrated in the accompanying drawing, wherein:

Figure 1 is a view in side elevation of a fragmentary portion of an ice-bag equipped with a closure constructed in accordance with my invention, the key for the closure being omitted,

Figure 2 is a top plan view of the ice-bag and closure,

Figure 3 is a sectional view taken on the plane indicated by the line 3—3 of Figure 2,

Figure 4 is a similar view with the key applied,

Figure 5 is a bottom plan view of the key, and

Figure 6 is a sectional view taken on the plane indicated by the line 6—6 of Figure 5.

Referring to the drawing by reference numerals, 1 designates the body and 2 the neck of an ice-bag which may be of any well known or appropriate construction.

The closure for the ice-bag 1 comprises a sleeve 3 which is screw threaded and suitably secured within the neck 2. The sleeve 3 is provided at its upper end with a radial flange 4 and an axial flange 5. The flanges 4 and 5 are annular, the flange 4 is provided in its lower side with an annular groove 6 for the reception of the upper end of the neck 2, and the flange 5 extends upwardly from the outer edge of the flange 4. A plug 7 is threaded in the sleeve 3, and is provided at its upper end with a radial flange 8 which overlies the flange 4. A gasket 9 is positioned between the flanges 4 and 8 to render the closure water-tight, and the flange 8 is provided in its under side with an annular groove 10 for the reception of the gasket. The upper end of the plug 7 and the flange 8 occupy, when the plug is in fully closed position, a position within the flange 5

and below the upper edge thereof. The upper surfaces of the plug 7 and flange 8 are smooth and concave, and the plug is provided in its upper end with spaced recesses 11.

The flanges 4 and 5 constitute a guard which prevents the removal of the plug 7 except through the medium of a key 12 which is adapted to be applied to the plug 7 in the manner illustrated in Figure 4. The key 12 is circular and larger diametrically than the flange 5, and is provided with a depending annular flange 13 which surrounds the flange 5 on the application of the key to the plug 7 and which constitutes a grip through the medium of which the key may be held firmly during the application and removal of the plug. To establish an operative connection between the key 12 and plug 7, the former is provided with downwardly extending lugs 14 which are adapted to engage in the recesses 11.

As the plug 7 cannot be removed from the ice-bag 1 without the aid of the key 12, which should always be in the possession of the nurse or attendant, it is impossible for a patient to gain access to the contents of the bag during the absence of the nurse or attendant. The closure and its key may be manufactured at a comparatively low cost, the former may be readily installed in the ice-bag, and the latter may be readily applied to and removed from the former.

It should be understood that the drawing is merely illustrative and does not pretend to give exact proportions. Furthermore, the said drawing is illustrative of a preferred construction, it being my expectation that various changes and modifications may be made without departing from the spirit and scope of my invention. While the closure is shown and described in connection with an ice-bag, it is to be understood that it is not limited to this particular use as it is adapted to and will be used in connection with hot water bags and the like.

What is claimed is:—

A closure for a bag provided with a neck, comprising a screw threaded sleeve secured within the neck, an annular flange extending outwardly from the upper end of the sleeve and provided in its lower side with an annular groove for the reception of the upper end of the neck, a screw threaded plug engaged in the sleeve and provided at its upper end with an outwardly extending annular flange over-

lying said first flange and provided in its lower side with an annular groove, a gasket positioned between said flanges and arranged in the groove of said second flange, the plug 5 being provided in its upper end with key engaging recesses, and an annular flange extending upwardly from the outer edge of said first

flange, said last flange surrounding the flange on the plug and extending above the plug and its flange to prevent the plug flange from being grasped in the hand. 10

In testimony whereof I affix my signature.

ARTHUR R. SODERQUIST.
